METHOD OF MAKING TORPEDO NETS

Alan E. Brickman, New Haven, Conn., assignor to
The American Steel and Wire Company of New
Jersey, a corporation of New Jersey

Application March 6, 1945, Serial No. 581,310

5 Claims. (Cl. 245—7)

1

This invention relates to a method of making a torpedo net and is particularly adapted for use with a nose catching type of torpedo net. Previous to my invention, the nose catching type of nets were made by fastening a plurality of grommets together. This construction was heavy, costly, and wasteful of material.

An object of my invention is to provide a method of making a torpedo net.

This and other objects will be more apparent after referring to the following specification and attached drawings, in which:

Figure 1 is a view of the completed netting;

Figure 2 is an enlarged plan view of the double barrel sleeve used in my net with a portion broken away and shown in section;

Figure 3 is a transverse sectional view of the sleeve of Figure 2 showing it fastened to ropes of the net;

Figure 4 is a schematic perspective view of the assembling apparatus, with the net being shown in outline only;

Figure 5 is a schematic view showing the method of assembling the sleeves on the ropes;

Figure 6 is an elevation of the apparatus used to fasten the sleeves to the ropes and to spread the net; and

Figure 7 is an end view of Figure 6.

Referring more particularly to the drawings, it will be seen that the net consists of a plurality of stranded wire structures 2, which are bent in zigzag arrangement in side by side relationship, the apices of the adjacent wire structures being connected by double barrel connectors 4 which are preferably of the type disclosed in my copending application, Serial No. 563,286, filed November 13, 1944, and entitled "Method and means for securing fittings to wire structures." The double barrel sleeve, as shown in Figures 2 and 3, consists of a body portion 6 having two longitudinal openings 8 therethrough and a small transverse opening 10 extending through the body between the openings 8 and intersecting said openings. This opening is adapted to receive a pin 12 of slightly greater diameter than the distance between the stranded wire structures 2 for holding the sleeve initially in place thereon. Further details and other modifications of the sleeve are disclosed in my above mentioned application. It will be seen that alternate sleeves on each wire structure are connected to the wire structures on opposite sides thereof. The outer circumference of the net is preferably formed of heavier wire structures 14 called boundary ropes, which are fastened to the mesh portion of the net by means of sleeves 16.

Figure 4 discloses net making apparatus which includes a table 18 having a reel support 20 at one end thereof for supporting a reel 22 of stranded wire structure and a cut off wheel 24 adjacent the reel 22 for cutting the stranded wire structure to the desired length. A power driven roll 26, supported on roller bearings 28, is provided at the exit end of the table for pulling the assembled net from the table. In making the net, the stranded wire structure is pulled from reel 22 and cut to the desired length by means of the cut off wheel 24. These lengths of wire structure form members 2 in the completed net and are of substantially the same length as the width of the unspread net. After a number of lengths have been cut, the sleeves 4 are passed over adjacent stranded structures 2. Since the sleeves 4 on one stranded structure are connected to the stranded structure on each side thereof, it is necessary that the sleeves be passed progressively over adjacent wire structures, and this is preferably done from the center of the strand outwardly to each end thereof. In other words, as shown in Figure 5, a sleeve A is first placed over the first two strands and moved to the center thereof, and a second sleeve B is passed over the third and fourth strands and moved to the center thereof. From each end a sleeve C is then passed over the second and third wire structures, and a sleeve D over the first and second wire structures. A sleeve E is then passed over the third pair of wire structures and moved to the center thereof, and a sleeve is passed progressively from each end over the fourth and fifth wire structures, the third and fourth wire structures, and first and second wire structures, these being sleeves F, G, H, and I, respectively. This operation is continued until the sleeves have been placed over the first and second wires for the full width of the net, the sleeves being added in alphabetical order as shown in Figure 5. At this time, it will be apparent that the sleeves will be placed on the wire structures on table 18 within the triangle indicated by the dash-dot lines 30, 32, the base of the triangle being formed by the wire structure located at 34. At this position, the sleeves are spaced the desired distance apart and fastened to the wire structures 2 by means of the pins 12. If desired, the sleeves could all be added from one end of the wire structures in progressive fashion, so that all the clips will be on the wire structures between the right hand side of the table 18 in the direction of travel, and the dash-dot line 30. However, this is not desirable from the standpoint of efficiency, since the op-

erators will be too close together on one side of the table. Additional stranded structures are then added on the assembly end of the net, and sleeves are progressively added from the base of the triangle to the apex thereof along lines 30 and 32 and pinned to the stranded structures on these lines. The operation may be performed continuously by pulling the assembled net along the table and adding wire structures at the charging end of the table as the net is pulled away from that end. After sufficient net has been assembled to pass from the table 18 over the roll 26, the roll will pull the net along the table 18. From the roll 26 the net passes downwardly around a second roll 36. Between the rolls 26 and 36 the sleeves 4 are swaged to the wire structures 2 and the net is spread by bending the stranded structures to beyond their elastic limit as they leave the sleeves 4. This is preferably done by means of a plurality of swaging devices 38 mounted on a track to provide horizontal traverse for the full width of the net. Due to the weight of the net, the stranded structures 2 will separate somewhat so that the sleeves 4 may be swaged to the wire structures by means of swaging rolls 40 which are keyed to shafts 42 and which may be rotated in either direction by any suitable means. The swaging rolls have parallel grooves 44, which together form an aperture slightly smaller than the outside contour of the sleeves 4.

Movement of the net assembly over the rollers 26 and 36 is stopped and the net secured with a row of sleeves 4 in horizontal alignment with the swaging rolls 40. Rotation of the swaging rolls is stopped so as to provide entry of the two strands just to the right of the sleeve. Power is then applied to the rolls to rotate them in the direction of the arrows in Figure 6 and as the grooves come around the sleeve 4 is fed therebetween. The pressure exerted on the periphery of the sleeve causes cold flow of the metal within the holes on into the interstices of the strand to bring about a fast connection. This method of fastening the sleeve on the wire structures is explained in detail in my above identified application. The net is preferably spread at this point by bending the stranded structures beyond their elastic limit as they leave the sleeves 4. This may be done by providing a spreader cam 46 at the inlet and exit sides of the rolls 40, only one of which operates at a time. When using this means of spreading the strands, the right hand spreader cam is drawn out in line with the roll grooves, as shown in Figure 6, and the left hand spreader cam is pushed back out of line into inoperative position. Rotation of the rolls is stopped in the manner described above so as to provide entry of the two strands just to the right of sleeve 4. The top strand is carried over the top and the bottom strand under the bottom of the right hand spreader cam 46. Power is applied to the rolls to rotate them in the direction of the arrows shown in Figure 6 to swage the sleeve 4 on the wire structures 2. In the power driven travel of the sleeves the two strands are form bent, as shown, to take a desired permanent spread. Power is cut off while the sleeve is still within the grooves 44 and the left hand spreader cam is brought out into line with the grooves and the top strand brought over and the bottom strand under the spreader cam. Power is reversed and the strands leaving the left hand end of sleeve 4 are form bent to take a permanent spread similar to the strands leaving the right hand end. The rolls 40 are then turned to a point where the swaged sleeve 4 can

be withdrawn and the machine is advanced toward the right to carry out a like cycle on the next sleeve. All three swaging machines 38 may be operated at the same time. The completed net is cut to the desired length after leaving the roll 36, and if boundary ropes 14 are used they may be added at this time.

While one embodiment of my invention has been shown and described, it will be apparent that other adaptations and modifications may be made without departing from the scope of the following claims.

I claim:

1. The method of making a zigzag weave net which comprises placing a plurality of stranded wire structures of a length substantially equal to the width of the unspread net side by side in substantially parallel relationship, progressively passing double barreled sleeves over adjacent stranded structures from the center outwardly to each end thereof, spacing the sleeves at the desired position along the stranded structures to obtain the desired openings in the finished net, thereafter applying sufficient pressure to the sleeves to secure them to the stranded structures, and spreading the net by putting a permanent bend in structures in the plane of the net at the point where they leave the sleeves.

2. The method of making a zigzag weave net which comprises placing a plurality of stranded wire structures of a length substantially equal to the width of the unspread net side by side in substantially parallel relationship, progressively passing double barreled sleeves over adjacent stranded structures from the center outwardly to each end thereof, spacing the sleeves at the desired position along the stranded structures to obtain the desired openings in the finished net, thereafter applying sufficient pressure to the sleeves to secure them to the stranded structures, and at the same time spreading the net by bending the stranded structures beyond their elastic limit in the plane of the net at the point where they leave the sleeves.

3. The continuous method of making a zigzag weave net which comprises placing a plurality of stranded wire structures of a length substantially equal to the width of the unspread net side by side in substantially parallel relationship, progressively passing double barreled sleeves over adjacent stranded structures from the center outwardly to each end thereof, spacing the sleeves at the desired position along the stranded structures to obtain the desired openings in the finished net, adding additional stranded structures at the un-assembled end of the net, and then repeating the above steps.

4. The continuous method of making a zigzag weave net which comprises placing a plurality of stranded wire structures of a length substantially equal to the width of the unspread net side by side in substantially parallel relationship, progressively passing double barreled sleeves over adjacent stranded structures from the center outwardly to each end thereof, spacing the sleeves at the desired position along the stranded structures to obtain the desired openings in the finished net, repeating the above steps, applying sufficient pressure to the sleeves to secure them to the stranded structures, and spreading the net by bending the stranded structures beyond their elastic limit in the plane of the net at the point where they leave the sleeves.

5. The method of making a zigzag weave net which comprises placing a plurality of stranded

wire structures of a length substantially equal to the width of the unspread net side by side in substantially parallel relationship, progressively passing double barreled sleeves over adjacent stranded structures from at least one end of the stranded structures, arranging the double barreled sleeves on said stranded wire structures so that adjacent sleeves along the length of the stranded structures will have only one common stranded structure therethrough, the other stranded structures through the adjacent sleeves being on opposite sides of the stranded structure common to both sleeves, spacing the sleeves at the desired position along the stranded structures to obtain the desired openings in the finished net, thereafter applying sufficient pressure to the sleeves to secure them to the stranded structures, and spreading the net by putting a permanent bend in the structures in the plane of the net at the point where they leave the sleeves.
